Primary Examiner — Ricky Pham(74) *Attorney, Agent, or Firm* — Beeson Skinner Beverly, LLP(57) **CLAIM**

The ornamental design for a stovetop smoker, as shown and described.

DESCRIPTION

FIG. 1 is a top perspective view of a stovetop smoker showing my new design;

FIG. 2 is a front elevational view thereof;

FIG. 3 is a right side elevational view thereof; the left side being a mirror image;

FIG. 4 is a rear elevational view thereof;

FIG. 5 is a top plan view thereof; and,

FIG. 6 is a bottom plan view thereof.

The broken lines in FIGS. 1 to 5 showing a handle on the top cover of the stovetop smoker forms no part of the claimed design. The broken lines in FIGS. 1 to 6 showing handles on the left and right sides of the base of the stovetop smoker form no part of the claimed design. The broken lines in FIGS. 1 to 5 showing a thermometer on the top cover of the stovetop smoker form no part of the claimed design. The broken lines in FIG. 6 showing ribs on the bottom of the base of the stovetop smoker form no part of the claimed design.

1 Claim, 6 Drawing Sheets(56)
